[57] CLAIM

The ornamental design for a dispenser for liquids or the
like, as shown and described.

DESCRIPTION

FIG. 1 is a perspective view of a dispenser for liquids or
the like showing our new design;

FIG. 2 is a side elevational view, the opposite side being
a mirror image thereof;

FIG. 3 is a top plan view;

FIG. 4 is a bottom plan view;

FIG. 5 is a front elevational view; and

FIG. 6 is a rear elevational view thereof.

FIG. 2

FIG. 1

FIG. 4
